(57) **CLAIM**

The ornamental design for a cast inlay, as shown and described.

DESCRIPTION

FIG. 1 is a top view of a cast inlay showing my new design. FIG. 2 is a perspective view of the cast inlay in FIG. 1 as applied to a cast.

FIG. 3 is a top view of the cast inlay in FIG. 2.

FIG. 4 is a side view of the cast inlay in FIG. 2.

FIG. 5 is a bottom view of the cast inlay of FIG. 2; and,

FIG. 6 is a side view of the cast inlay in FIG. 2.

The broken lines in the drawings represent environmental subject matter and form no part of the claimed design.
